UNITED STATES PATENT OFFICE.

JAMES H. REINHARDT, OF EAST ORANGE, NEW JERSEY, ASSIGNOR TO AMERICAN BANK NOTE COMPANY, OF NEW YORK, N. Y., A CORPORATION OF NEW YORK.

NUMBERING MACHINE.

Application filed May 14, 1924, Serial No. 713,149. Renewed October 15, 1926.

My invention relates to numbering machines, and more particularly to a rotary machine of this type.

Heretofore numbering machines and the numbering heads used thereon, have been so constructed that the digit wheels of the latter have been progressively actuated by a spring-pressed plunger engaging the platen of the impression cylinder or bed, or a striker member associated with the numbering head cylinder, or by a spring-restored oscillatory arm, the wheels of denominations higher than the units being actuated by a transfer mechanism forming a part of the numbering head.

The manner of actuating the numbering heads in such machines has been such that each digit wheel of each numbering head, has of necessity had associated therewith a spring pawl or pawls for checking the rotation of the digit wheel, or locking it against rotation, either or both of said pawls also being utilized for accurately positioning or justifying each digit wheel as it was brought into the printing position. Such pawls were required not only to ensure accuracy in the mechanical actuation of each digit wheel, but also to prevent the accidental turning of a digit wheel of one denomination with a digit wheel or wheels of another or other denominations as a result of the accumulation and hardening of ink between the digit wheels, and the movement of said digit wheels with relation to the inking rolls of the inking mechanism.

In machines utilizing numbering heads of the character above referred to, the breakage of any of the many springs about the numbering head, and the breakage of the spring upon the plunger or other actuating means will result in failure of the consecutive actuation of the digit wheels, and thus cause duplication of numbers requiring in the case of bank notes, stocks, bonds, or other negotiable securities, a hand or machine numbering of separate instruments to replace those upon which the numbers were duplicated. In fact the highest degree of care and skill in inspecting such instruments, is required to avoid such duplication of numbers and to avoid the making of replacement instruments with the proper numbers there-

on; and it is not infrequent, that instruments thus bearing duplicate numbers are not detected, thus causing great confusion, which may not develop for a long period after the issuance of such instruments.

In machines of the character above referred to, the various numbering heads of succeeding groups or units are successively actuated, although it has been purposed to so construct a numbering machine that all of the numbering heads thereon will be simultaneously actuated by means of a single mechanism operative upon the units wheel, and therethrough upon wheels of higher denominations.

With the above conditions in mind, I have provided a numbering machine in which none of the actuating mechanisms are acted upon by springs, and which will actuate the various numbering heads thereon in a manner permitting the use of heads without the ordinary detent and locking pawls.

In the machine of my invention, the actuating mechanism is simultaneously operative upon the corresponding digit wheels of the numbering heads of all groups upon the machine, these wheels being positively held by mechanisms in the machine against movement except under the control of said actuating mechanism.

The construction of, and arrangement of parts in, the machine is such that the transfer mechanism for all of the numbering heads is incorporated as a part of the mechanism of the machine, and are brought into operation as required, as a result of the rotation of the numbering head cylinder.

The construction of the actuating mechanism is such that, at all times including during the operative interval of the mechanism acting to progressively advance the printing wheels of the numbering heads, any movement of such wheels by accident is prevented. The actuating mechanism includes therein devices by which the member operative upon the numbering heads will be normally positively locked and will be released only during that short interval required to actuate the digit wheels. The controlling mechanism for the actuating means for the various numbering heads is so constructed

as to have its movement accurately timed with relation to other parts of the actuating mechanism.

While the controlling mechanism for the 5 units digit wheels of the various numbering heads is so constructed and actuated as to be operative during each rotation of the numbering head cylinder, the controlling mechanisms for the tens and the hundreds digit 10 wheels are so constructed as to be operative only upon each tenth or each one hundredth rotation of said numbering head cylinder, the transfer operation as to these digit 15 wheels being affected through the controlling mechanism of the machine, instead of through mechanisms in the numbering heads. The thousandths wheel of each numbering head may receive timely actuation through 20 mechanisms in the numbering head, this being preferable to simplify the mechanisms in the machine as well as in the numbering heads themselves. Wheels of still higher 25 denomination, while they may be actuated in the same manner as the thousandths wheel, may also be set by hand. These conditions are possible in a machine utilized primarily for numbering security paper, where the runs are short and accuracy takes precedence over high capacity output.

30 In a machine embodying my invention, the numbering heads of the different groups may be set circumferentially of the cylinder very close together, or at spaced distances as desired, close setting of such heads being desirable when numbering bond coupons, and setting of the heads a greater distance apart adapting the machine for other kinds of work. The construction of the machine is such as to permit the setting of the heads 35 with great nicety as to succeeding groups of heads, and to ensure accurate alinement longitudinally of the cylinder, of the different heads in each group.

In a machine embodying my invention, 40 numbering heads may be used which contain few parts, as compared to the ordinary numbering heads, these heads being of great simplicity while still being reliable in their operation. The manner of actuating the 45 heads by the machine is such as to ensure positive accuracy as to the alinement of the printing characters upon the digit wheels of each head as well as upon heads of each group.

In conjunction with other mechanisms in 50 the machine, I provide a throwoff mechanism by which the impression cylinder may be moved out of the printing position in relation to the numbering head cylinder, this throwoff mechanism simultaneously making 55 the controlling mechanism for the actuating mechanisms for the numbering heads, inoperative, and at the same time making the 60 means for progressively operating the controlling mechanisms inoperative so that the 65 various mechanisms in the machine may be

restored to their former positions without having had the mechanisms for ensuring the sequential operation of the various digit wheels so actuated as to have changed the 70 sequence of operation of any of the wheels upon succeeding impressions as compared with the ordinals printed prior to the actuation of said throwoff mechanism.

The machine embodies various other mechanisms for ensuring accuracy in the 75 timing of the actuation of the digit wheels and their quantity of movement, and to secure the proper alinement of the printing characters of the numbering heads. The construction and arrangement of parts is 80 such as to compensate for slight inaccuracy of parts either in workmanship or due to wear, and to prevent accumulation of error as a result of a continued run of the machine in the presence of any slight in- 85 accuracy.

The invention consists in the novel features of construction and combination of parts hereinafter set forth and described, and more particularly pointed out in the claims 90 hereto appended.

Fig. 13 shows the position of parts upon the final movement of said mechanism by the controlling mechanism which will leave the parts in the position shown in Fig. 10. 130

Like numerals refer to like parts throughout the several views.

In the embodiment of my invention shown in the drawings, the impression cylinder 15 has associated therewith a feed shelf 16 and a delivery tape mechanism 17. Co-operating with the cylinder 15 is a numbering head cylinder 18 having a hub provided with circumferential flanges 19 adapted to form a suitable backing for a depending flange 20 upon each, of a plurality of frames 21, said frames respectively being adapted to support a group of numbering heads indicated at 22.

Each frame 21 has, at each end thereof, a tongue 23 adapted to fit a T-slot 24 formed in each end plate 25 of said cylinder 18. The perimeter of said plate is provided with graduations, or gauge markings, 26 permitting great nicety in the adjustment of the 20 opposite ends of the frames 21 in securing the desired accurate alinement of the digit wheels of the different numbering heads carried by each of said frames. Said frames 21 may be secured in adjusted position upon the end plates 25 by means of set screws 27, or other locking means for securing said tongues 23 in a fixed relation to the T-slots 24.

Each of said frames 21 has mounted therein a group, or a sequence of groups, of digit wheels 22 so associated and combined therewith as to permit adjustment of the different units of each group laterally of the machine with relation to each other, each group, or associated groups, being simultaneously adjusted circumferentially of the machine with relation to other groups, by movement of the frame carrying same.

In the form of the invention shown, the construction of the numbering head mechanism is such that the units, the tens and the hundreds digit wheel of each head, are consecutively and progressively operated by a digit wheel actuating mechanism, the operative effect of which is controlled by what may be termed a controlling mechanism, this last named mechanism being actuated as a result of the rotation of the cylinder 18. The construction and mode of operation of these various mechanisms will be more fully described hereinafter, it being merely desired at this point to emphasize that while the frames 21 and the various units 22 properly constitute the numbering heads to be used in the machine, the mechanisms for imparting timely rotary movement to the various digit wheels, form a part of the machine proper, as distinguished from the numbering heads. These mechanisms are simultaneously operative upon all numbering heads carried by said cylinder 18 as to digit wheels of the same denomination in the different heads. Adjustment of the heads of each group with relation to each other or to those of other groups, may be had entirely independently

of the actuating mechanisms, this, however, following in part from the particular construction of the head, and in part from the mechanisms of the machine.

Each of the frames 21 in the form of the invention shown, has mounted therein three shafts 28, 29 and 30, each of which is provided with a gear. One of these shafts as 28 is connected directly with, or geared to, all of the units wheels of the group or groups carried by the frame in which it is mounted, and is provided with a ten-tooth gear 31 projecting beyond the end plate 25. Another of these shafts as 29 is either directly connected with, or geared to, all of the tens wheels of each group or groups carried by the frame 21 in which this shaft is mounted, and has a gear 32 positioned beyond the end plate 25 but upon a plane parallel with the gear 31. The remaining shaft 30 is connected in a manner corresponding to that heretofore described with all of the hundreds wheels of the group or groups carried by the frame 21 in which it is mounted, and carries a gear 33 positioned beyond the end plate 25, upon a plane parallel from that of either of the other gears 31 or 32. With the arrangement of parts shown in the drawings, the gear 31 is more remote from the plate 25 than either of the other gears; the gear 33 being adjacent to said plate 25, and the gear 32 occupying a position intermediate said two other gears.

In the form of the invention shown, the construction of numbering head is such that the shaft 28 acts directly upon its digit wheels, while the shafts 29 and 30 act upon their digit wheels through gears in the numbering head proper. Hence it is possible to have the shafts 28 and 29 the same radial distance from the axis of the cylinder 18, it being necessary, however, to have the shaft 30 at a shorter radial distance from said shaft.

While the construction of the numbering heads 22 forms no part of the present invention, I may state that possible variance in the construction of such heads is such that the shafts 28 and 29 may both be directly connected with the digit wheels operated thereby, but that the third shaft 30 will of necessity be connected with its wheels by a gear or gears.

While I have referred to these three shafts as being connected with, or operative upon, digit wheels of certain denominations, it is apparent that by re-arrangement of parts in the machine, these shafts may be associated with wheels of other denominations than those specifically referred to in connection with the particular embodiment of the invention shown in the drawings.

Each of the gears 31, 32 and 33 of each frame 21 carried by the cylinder 18, co-operates with its own actuating mechanism,

4
said actuating mechanisms being identical in construction and mode of operation, excepting for that difference due to the different radial distances of the gears 31 and 32 and the gear 33 from the axis of the cylinder 18, and in the timing of the operation of these different mechanisms, which, however, is determined by a controlling mechanism having members operative upon said actuating mechanisms but at different intervals as determined by necessary transfer operations as to the different numbering heads during the operation of the machine and the resultant progressive actuation of the digit wheels of the numbering heads. This controlling mechanism is actuated from the cylinder 18 so as to ensure accuracy in the timing of the transfer operation through the actuating mechanism, in accordance with the number of impressions made by the numbering heads carried thereby, and the initial setting of the heads of the different groups.

The actuating mechanism for the digit wheels above referred to, consists of three gears 34, 35 and 36, the first of which meshes with the gears 31, the second of which meshes with the gears 32, and the last of which meshes with all gears 33, of each unit. These gears 34, 35 and 36 are idly mounted upon one of the arbors of the cylinder 18 being capable of rotation with and about the same axis as said cylinder, when it is not required to impart any movement to the digit wheels of the numbering units, and yet be capable of movement independently of and in the same direction as, said cylinder when it is desired to progressively actuate the digit wheels.

Carried by, and rotatable with, the cylinder 18 adjacent each gear 34, 35 and 36, is an arm 37, 38 and 39 extending to a point beyond the periphery of the gears 34, 35 and 36 respectively, and positioned closely adjacent said gears.

Each of the arms 37, 38 and 39 carries a mechanism co-operating with its gear including a member which, at all times, including during the interval when it is required to actuate the gear to advance the digit wheels, serves to connect its gear with the cylinder 18. This mechanism is so actuated, when it is required to turn said gears independently of the cylinder 18 for the purpose of imparting movement to its digit wheels, as to momentarily disconnect one part of said mechanism from said gear, and impart the desired movement to said gear by another part of said mechanism while it is so disconnected, without, however, disconnecting said gear from said cylinder.

The mode of operation of this mechanism is such that instantly upon the completion of the movement of its gear, independently of the numbering head cylinder, it is restored to its normal position connecting said gear

with said cylinder. These mechanisms are indicated as units by the reference letters, A, B and C, the different parts of each of these mechanisms being hereinafter indicated by the same reference numerals, since each of these mechanisms is in its construction, timing and mode of operation, a duplicate of the other.

Since the actuating interval for each of the gears 34, 35 and 36 will be the same as that of the others, the various arms 37, 38 and 39 project along the same radius of the cylinder 18, or substantially so, in order to simplify the construction and mode of operation of the mechanism which controls the operative interval of each of the mechanisms A, B and C.

Referring more particularly to Figs. 10 to 13 of the drawings, in which an actuating mechanism such as A is shown, each of said mechanisms comprises a pivotal locking member 40 having two groups of teeth 41 and 42 thereon, adapted respectively and alternately to mesh with the gear 34. This member 40 is pivoted intermediate its ends to the arm 37 at 43, and is so formed that with an oscillatory movement of said member in one direction, one set of teeth as 41 will be disengaged from the gear 34 before the other set of teeth 42 will engage with the teeth upon said gear. The interval during which both sets of teeth 41 and 42 are thus disengaged from said gear, affords sufficient time for the movement of said gear independently of the cylinder 18 by a mechanism carried by said member 40, the operation of which results in part, from the oscillatory movement of said member 40.

After each oscillatory movement of the member 40 in a direction to thus cause movement of the gear 34, a return oscillatory movement is imparted thereto by the controlling mechanism, resulting in the disengagement of the teeth 42 from said gear 34, and the re-engagement of the teeth 41 therewith, all of these operations occurring while the cylinder 18 and the arm 37 are having similar rotary movement.

Pivotedly mounted upon the member 40 adjacent the teeth 41 is a double toothed dog 44, the two teeth 45 and 46 of which are spaced apart a distance greater than two teeth of the gear 34, but a distance less than three teeth. While the pivotal support for said dog 44 will permit it to have free movement, I provide said member 44 with a friction plate 47, bearing against the side of its gear 34, so as to avoid a displacement of this part by centrifugal force or otherwise, while it is turning with the arm 37 and gear 34. The point of pivotal support of the dog 44 is such with relation to the pivot 43 for the member 40, that oscillatory movement of said member as a result of its engagement with the controlling mechanism, will cause a thrust

to be exerted by the dog 44 upon its gear 34, the movement of said member 40 being sufficient to cause said dog to advance the gear 34 a distance equal to that between the centers of succeeding teeth upon said gear, as a result of each actuation of said member 40.

The dog 44 carries a laterally projecting impact wheel 48 adapted to be engaged by the controlling mechanism for ensuring the proper engagement of the tooth 45 of said dog with a tooth of the gear 34. The member 40 is in the nature of an escapement which is operated at predetermined intervals following the completion of the making of impressions upon each sheet of paper on the cylinder 15 and the numbering heads 22 of the various groups carried by the numbering head cylinder 18.

These cylinders 15 and 18 are connected by intermeshing gears 49 and 50, and the various numbering heads 22 are inked by means of the inking mechanism 51 so positioned with relation to the printing line of the two cylinders as to apply ink to the digit wheels of the numbering heads following each actuation of said digit wheels.

Since the gear 34 actuates the units digit wheel only, the gear 35, the tens wheels, the gear 36 the hundreds wheels, it is apparent that the controlling mechanism operative upon the mechanism A, B, and C must be so constructed and arranged and so operated, that it will act upon the mechanism A with each revolution of the cylinder 18, the mechanism B, upon each tenth revolution thereof only, and the mechanism C upon each hundredth revolution, and that the actuating mechanism for said controlling mechanism must be operated in a manner determined by the number of rotations of the cylinder 18.

In the embodiment of the invention shown, I employ three cam bars 52, 53 and 54, adapted respectively to co-operate with the levers 40 of the mechanisms A, B and C, and with the impact wheels 48 carried by the dog 44 of said mechanisms A, B and C respectively.

Each of these cam bars has a riser as thereon, arranged so as to be positioned in the path of movement of the member 40 of its co-operating mechanism A, B or C, and a riser 56 in the path of the wheel 48, these risers being so positioned that the riser 56 will be engaged by the wheel 48 before the member 40 is engaged by the riser 55, and this latter engagement will occur while the wheel 48 is still engaged with the riser 56.

The member 40 has two enlargements thereon at 57 and 58 respectively, both so positioned as to engage the riser 55, so that this riser will act thereon to impart oscillations to the member 40 alternately in opposite directions, as said member passes said riser 55 during each operative interval of

the controlling mechanism in relation to said member.

Under normal working conditions in the machine, the controller bar 52 is maintained continuously in the path of movement of the member 40 of the mechanism A, the bar 53 being brought into the path of movement of the mechanism B upon each tenth rotation of the cylinder 18, but being positioned out of the path of movement of said mechanism B during other revolutions of said cylinder, while the bar 54 is brought into the path of movement of the mechanism C only upon each one-hundredth revolution of said cylinder 18, being positioned out of the path of movement of said mechanism at all other times. To secure the desired actuation of said controller bars, it is therefore necessary to provide an actuating mechanism for said bars which, while it is actuated with each rotation of the cylinder 18, will act differentially upon the controller bars 52, 53 and 54 in the respects above noted. This mechanism is so constructed as to avoid any possible variation from an accurate timing of the actuation of said controller bars with relation to the controlling mechanisms and the rotation of the cylinder 18.

In securing the desired actuation of the controller bars and the parts appurtenant thereto, I provide movable members operative upon the controller bars 52, 53 and 54 respectively, one of which members is adapted to normally maintain the controller bar operative upon the actuating mechanism for the units digit wheels in the operative relation to said actuating mechanism at all times. Another of these members is provided with ten risers adapted to successively co-operate with the controller bar operative upon the actuating mechanism for the tens digit wheels, these risers being so positioned as to normally maintain said controller bar out of the path of movement of its co-operating actuating mechanism, but to move said bar into the path of movement of said mechanism once during each ten revolutions of the cylinder 18. The third member contains a single riser having the same operative effect upon the controller bar co-operating with the actuating mechanism for the hundreds digit wheels as the movable member with the ten risers, but being normally operative to maintain said controller bar out of the path of movement of its co-operating actuating mechanism at all times excepting during the one-hundredth rotation of the cylinder 18. By having the first of these members without risers of any kind, but having the risers upon the other two members in a ratio of ten to one in the manner described, it is possible to impart similar simultaneous movement to said members, the amount of said movement being one-tenth of the complete cycle of move-

ment of each member with each ten revolutions of the cylinder 18, thus preserving the proper timing interval of the actuation of the digit wheels actuating mechanisms 5 through similar movements of these dissimilar members, and controlling the actuation of all of these members by a mechanism receiving power from the cylinder 18.

In the form of the invention shown, the 10 movable members above referred to consist of three disks 59, 60 and 61 each carried by, and rotatable with, the same shaft 62 mounted in a frame 63 positioned below the bars 52, 53 and 54. The disk 59 is a true circle 15 and constantly engages the bar 52 so as to normally hold the said bar 52 in a position where the risers 55 and 56 upon said bar will be in the path of movement of the member 40 of the mechanism A. The disk 20 60 has ten risers 64 thereon adapted to co-operate with a cam tooth 65 upon the bar 53. The fall between adjacent risers 64 is so formed as to receive the cam tooth 65, the setting of this disk 60 being such that under 25 normal conditions the tooth will be in the fall between risers so as to normally maintain the cams 55 and 56 of the bar 53 out of the path of movement of the member 40 of the mechanism B.

30 The disk 61 has a single riser 66 thereon adapted to co-operate with a cam tooth 67 upon the bar 54.

The shaft 62 is acted upon by an intermittent mechanism receiving one impulse during 35 each rotation of the cylinder 18, and imparting one impulse to the shaft 62 upon each tenth rotation of said cylinder 18. This intermittent mechanism in the form of the invention shown, comprises a Geneva 40 stop movement, the Geneva gear 68 of which has twenty teeth, and the co-operating gear 69 of which, has two teeth so set as to engage succeeding teeth of the Geneva gear and thus impart two separate movements to the gear 68 upon two succeeding impulses imparted by the gear 69. The gear 68 is carried by the shaft 62 while the gear 69 is carried by a shaft 70 which also carries two ratchet wheels 71 and 72, the teeth of which 45 are oppositely set so that by the use of synchronized actuating and holding pawls, a positive rotative movement to a limited extent may be imparted to said shaft 70 through one of these ratchet wheels, as 71. 50 The shaft 70 is mounted in the frame 63. Actuated by the gear 69 is a holding pawl 73 operative upon the gear 68.

Mounted upon the shaft 70 is a swing arm 74 having pivotally mounted thereon by 55 means of the pivot 75, a pawl 76 co-operating with the ratchet wheel 71. Pivotally connected with the swing arm 74 by the pivot 75 is a lift rod 77, one portion of which is slotted as shown, and straddles one of the 60 arbors of the cylinder 18. This lift rod 77

carries an impact wheel 78 adapted to be engaged by a cam 79 upon the shaft of the cylinder 18. Hence, the lift rod 77 will impart movement to the swing 74 and pawl 76, during each rotation of said cylinder 18.

The ratchet wheels 71 and 72, each have 75 ten teeth, and each actuation of the swing arm 74 will be such as to impart a one-tenth rotation to said ratchet wheels and to the gear 69 carried by the shaft 70. The impact wheel 78 is so set that the rod 77 will reach the highermost position during its movement immediately following the completion of the second oscillatory movement of the member 40 for operatively connecting the gear wheels 31, 32 and 33 with the cylinder 18, in the manner heretofore described. The weight of the rod 77 and arm 74, and the parts co-operating therewith is sufficient 80 to ensure a return movement of these parts following each actuation thereof by the cam 79.

The cam 79 is so formed as to impart an upward movement to the bar 77 to ensure 85 the bars 53 and 54 being brought into the operative relation to the mechanisms B and C with the proper timing with relation to the movements of said mechanisms with the cylinder 18, and an advancement of the gears 32 and 33 by the actuating mechanisms therefor, and the restoration of said bars to their normal inoperative position as a result 90 of the movement of the disks 60 and 61, upon the succeeding actuation of the intermittent mechanism above described. Co-operating 95 with the ratchet wheel 71 is a gravity detent pawl 80, the movement of which is limited by the stop pin 81, so as to minimize the tendency of a sudden movement of the wheel causing an overthrowing of this pawl.

The undercut teeth 82 upon the ratchet wheel 71, and the reduced interlocking end 100 of the pawl 76, are for the purpose of preventing said pawl from overriding said ratchet teeth with a possible resultant skipping in the actuation of the controller bars, such an action of the machine being fatal.

In order to ensure a timely actuation of the disks 59, 60 and 61 through the ratchet wheel 71, I associate with the ratchet wheel 115 72 carried by and rotatable with the shaft 70, which carries said wheel 71 and the gear 69, a stop pawl mechanism so constructed as to prevent any movement of said shaft 70 except as a result of the engagement of the pawl 76 with a tooth of the ratchet wheel 71, and at the same time limit the movement of said ratchet wheel to a degree in arc corresponding with the movement of said 120 pawl 76.

This pawl mechanism comprises two gravity pawls 83 and 84, pivoted upon an extension 125 85 carried by the frame 63. The pawl 83 has a cam slot 86 therein, through which the pivot 75 passes, this cam slot being so 130

formed that during the initial movement of the swing arm 74 and before the pawl 76 is engaged with a tooth upon the ratchet wheel 73, said pawl 83 will be moved out of engagement with a tooth upon the ratchet wheel 72, and thus permit the free turning of the shaft 70 following the engagement of said pawl with said wheel. The pawl 84 is normally disengaged from the ratchet wheel 72, being held out of engagement therewith by a pin 87 carried by the pawl 76. Said pawl 84 has therein a cam slot 88 through which the pivot pin 75 passes, said slot being so formed that substantially simultaneously with the movement of the pawl 83 out of engaging relation with the ratchet wheel 72, said pawl 84 will be moved toward said ratchet wheel to a position where it will engage the succeeding tooth thereon, and will 20 continue in this position during the rotation of the ratchet wheel 72 and shaft 70 by the pawl 76. These movements will occur during the upward movement of the swing arm 74 by the lift bar 77, and will be reversed 25 during the return or downward movement of said lift bar. In this manner the shaft 70 is normally held against movement except under the control of the pawl 76, and the extent of its movement is limited to that required to ensure against overrunning of the 30 disks 59, 60 and 61. The pawl 80 serves to prevent an accidental return movement of said shaft.

The pawl 76 is maintained in the proper 35 relation to the wheel 71 by a pin 89 carried by the lift rod 77 and working in a recessed portion of said pawl 76.

I have referred to this double pawl mechanism as ensuring a timely actuation of the 40 controller mechanism, since overrunning of the gear 69 would have the effect of permitting downward movement of the members 53 and 54, prematurely.

In connection with the other mechanisms 45 in the machine, I provide a throwoff mechanism, the actuation of which will simultaneously bring the impression cylinder and the numbering head cylinder out of the printing relation one to the other, prevent 50 the actuation of the bar 77 by the cam 79, and bring all of the members 52, 53 and 54 out of the operative relation to the actuating mechanisms A, B and C. In this manner printing by the machine may be stopped at 55 any time, and actuation of the digit wheels of the various numbering heads will be prevented so long as no impressions are being made by the machine. The stopping and re-starting of the machine may therefore occur 60 at any time, without requiring resetting of any of the numbering heads, or the readjustment of any of the mechanisms operative thereon.

In the form of the invention shown, this 65 throwoff mechanism comprises a crank shaft

90, two cranks 91 and 92 of which are operatively connected by the links 93 and 94, with the pedals 95 and 96, one of which is for actuating this mechanism to stop the machine, and the other of which is for actuating said mechanism to start the machine. 70

Carried by the shaft 90 is a crank 97 connected by a link 98 with the striker roll 78, which is carried by an arm 99 pivotally connected with the lift bar 77, said crank also 75 being connected by a link 100 with a rocking lever 101, pivoted at 102, one arm of this lever 101 having pivotally connected therewith a link 103, the lower end of which is connected with the frame 63. This frame 80 85 is pivoted at 104. The shaft 90 is also provided with a crank 105 connected by a link 106, with a crank 107 upon the shaft 108, which shaft is connected by a toggle lever with the carriage 110, carrying the impression cylinder 15.

The operation of the herein described mechanism is substantially as follows:

As in ordinary numbering machines, the 90 numbering heads of each group will be set in accordance with the number of impressions on each sheet, both circumferentially and laterally of the cylinder 18, and the number of sheets which are to be run. If the job has twenty on, four rows of five, 95 and a run is to be one thousand sheets, corresponding numbering heads of one group will be set beginning with 1 on the first head, 1001 on the second, and successively increased by 1000 until the head of the last group is set at 4001. The adjoining head of the first group will be set at 5001, and the next head of that group at 10001, and the last head of that group at 15001. Corresponding heads of succeeding groups will 105 be successively advanced one thousand as compared with the corresponding head of the preceding group.

The manner of setting the heads is peculiar to the construction of the numbering heads and not to mechanisms of the machine, this being also true as to the lateral adjustment of the heads of the different groups for securing the proper spacing of the numbers with relation to the printed matter upon which they are to be impressed, previously printed sheets generally being used with machines of this type. 110

In positioning the different groups with 115 relation to each other, the set screws 27 are released, and the frames 21 in their entirety are moved circumferentially upon the end plates 25, the graduations or gauge markings 26 being followed for securing the desired accurate alignment of the heads of each group, parallel with the axis of the cylinder 18. When the proper adjustment has been made, the set screws 27 are set to hold the frames 21 in their adjusted position. 120 The frames 21 and the dependent flanges 20 125 130

thereon engaging the circular flanges 19 upon the cylinder 18, will impart great rigidity throughout the frames 21 and the numbering heads 22 carried thereby, so as to ensure equally sharp impressions by all of the numbering heads.

It may be noted that the length of the cylinder 18 in machines of this character, is never great, so that spring of the shafts 28, 10 29 and 30 will not occur, at least to an extent to interfere with the making of sharp impressions.

During substantially all of each rotation of the cylinder 18, the gears 34, 35 and 36 15 will be operatively connected with said cylinder 18 as a result of the engagement of the teeth 41 of the oscillatory member 40 of each of the mechanisms A, B and C with said gears respectively, since said members 20 40 are carried by the arms 37, 38 and 39 which are carried by and rotatable with the shaft of said cylinder 18. Hence not only will no movement be imparted to the gears 31, 32 and 33 and the shafts carrying same 25 through which the digit wheels are turned, but said gears and said shafts will be locked against any possible rotation by the same mechanisms which connect the gears 34, 35 and 36 with the cylinder 18.

After the numbering heads of the last group have passed the printing position, and before the numbering heads of the first group have reached the inking mechanism 51, the various actuating mechanisms A, B 35 and C will come into the operative relation to the controlling mechanisms therefor, and those digit wheels which require to be turned in order to secure the desired progressive advancement of the wheels, will receive a 40 movement amounting to one-tenth of a complete revolution thereof, this movement occurring simultaneously in all corresponding wheels of all groups of numbering heads.

In describing this progressive actuation of the units digit wheels, I will refer first to the actuation of the units wheels of the different numbering heads of the different groups, it being understood that so far as the operation of the actuating mechanism 50 itself is concerned, the operation of turning the units wheels is the same as to the tens or the hundreds wheels.

As the actuating mechanisms A, B and C approach the controller bars 52, 53 and 54 55 respectively, the cam 79 will become operative upon the impact roller 78 to raise the lift rod 77, and thus impart a one-tenth revolution to the two-tooth gear 70. Since the bar 52 is controlled by the circular disk 59, the cams 55 and 56 of said bar will always occupy the same position with relation to the path of movement of the actuating mechanism A, so that the movements of the lift bar 77 and the mechanism actuated

thereby will have no operative effect what- 65 ever upon this bar or in controlling or timing the actuation of the units digit wheels through the gear 34 and the mechanism A. The said cam 79 and said lift bar 77 are employed merely for ensuring the timely 70 actuation of the gear wheels 35 and 36 with relation to the rotary movement of the cylinder, the disk 59 being, in fact, merely for the purpose of supporting the bar 52 in its fixed or zero position and for controlling 75 the movements of the bar 52 upon the actuation of the throwoff mechanism.

As the oscillatory member 40 of the mechanism A approaches the bar 52, the roll 48 upon the dog 44 by engagement with the cam 80 56 of said bar, will completely mesh the tooth 45 of said dog with a tooth of the gear 34, without, however, imparting any movement whatever to said member 40. The friction device 47 permits this oscillatory 85 movement of said dog, and at the same time tends to hold the dog in the position to which it is brought by said cam, and also its position with relation to the gear 34 at all other times.

Immediately following, and in fact, substantially simultaneously with the enmeshment of the tooth 45 with the gear 34, the cam surface 57 upon said member 40 will engage the cam 55 upon said bar 52, and 90 thus oscillate the member 40 about the pivot 43. The movement of said member 40 under the control of said cam 55 causes the end of said member adjacent the tooth 41 to describe an arc, and at the same time impart 100 a rolling motion to the dog 44. The initial arcuate movement of the point of pivotal support of said dog will impart slight rotary movement to the gear 34, and the rolling movement of the dog will mesh the tooth 105 46 thereof with a tooth upon the gear 34, so that the continued movement of the member 40 will disengage the tooth 45 and complete the rotative movement of the gear 34 under the control of the tooth 46. Substantially simultaneously with the conclusion 110 of the movement of the gear 34, to the extent of one tooth only, the teeth 42 upon the member 40 will mesh with the teeth upon the gear 34, thus arresting further movement of said gear and holding the gear in this position until, as a result of the continued movement of the arm 37 and of the gear 34 under the control of said arm and said member 40, the cam 58 of said member engages the cam 55 of the bar 52, whereupon, said member will receive a return oscillation to its former and normal position.

The pitch of the cam 56 is merely for the 125 purpose of compensating for the arcuate path of movement of the member 44 conforming to the circumference of the gear 34.

Upon the return oscillatory movement of the member 40, the teeth 41 thereon will be engaged with the succeeding teeth of the gear 34, thus again locking or connecting the arm 37 with said gear 34. Upon the return movement of the member 44, the tooth 45 thereon may or may not engage the succeeding tooth, the friction device 47 having the effect of preventing such engagement, 10 or tending to do so.

Hence, the cylinder 18 will, at all times, be connected with the gear 34 through the arm 37 and the member 40, this engagement being either by the teeth 41, by the teeth 42, 15 or by the tooth 45 or 46, the former being the normal method of connection, and there being a short interval between the disengagement of one of said sets of teeth 41-42, and the engagement of the other with said gear 34, during which interval however, the gear 34 will receive accelerated rotary movement to cause an advance of one tooth through the action thereon of the teeth 45-46. Hence, while the gear 34 is always 20 operatively connected with the cylinder 18 so as to turn therewith through the arm 37, and the actuating mechanism carried thereby, during a very short portion of each revolution, said gear 34 will receive an impulse amounting to a movement of one tooth with relation to said cylinder and said arm, while still being turned with said cylinder.

As a consequence of this condition, the gear 34 will always be turning with the cylinder 18, but will have a short interval of acceleration during each rotation of said parts. During that interval when the gear 34 and the cylinder 18 are turning at the same speed, the gear 31 connected directly 35 or indirectly with the units wheels of the various numbering heads 22 of each group will be held stationary, this interval including the entire printing interval for all groups upon the cylinder 18, as well as the inking interval as to all said groups, rotation of the digit wheels occurring between these two intervals.

Since the operation of each of the actuating mechanisms A, B and C is identical with that of the others, it is unnecessary to repeat a description of this mode of operation. It will suffice to state that, while the operation of the controlling bar 52 occurs upon each revolution of the cylinder 18 and gear 34, the operative interval of the controlling bars 53 and 54 will occur upon each tenth and each hundredth revolution of the gears 35 and 36 and the cylinder 18, these controlling bars acting as a common transfer mechanism operative respectively upon the tens and hundreds wheels upon the various numbering heads upon said cylinder 18. This result, while due primarily to the construction of the disks 60 and 61 is contributed to by the intermittent driving mech-

anism for these disks, which in turn is controlled from the cylinder 18.

As heretofore stated, upon each rotation of the cylinder 18, the cam 79 will, through engagement with the roller 78, lift the bar

70

77, and through the rock arm 74, pawl 76 and ratchet wheel 71 turn the shaft 70 one-tenth of a revolution. The pawls 83 and 84 co-operating with the ratchet wheel 72 operate

75

in the manner heretofore described, merely in safeguarding the actuation of the shaft 70 so as to limit the operative interval of said shaft with reasonable accuracy with relation to the position of the members 40 and the controller bars co-operating respectively

80

therewith. While the shaft 70 receives a one-tenth revolution, it will impart only a one-twentieth revolution to the shaft 62, thus causing the necessary one-tenth revolution of the shaft 62 to be divided into two stages as

85

to operative effect upon the disks 60 and 61 as a result of the double-toothed gear 69 carried by the shaft 70 and the twenty-toothed Geneva stop gear 68 co-operating therewith and carried by the shaft 62 carrying the disks

90

59, 60 and 61. During the first stage of this movement, which will include one-tenth of a revolution of the shaft 70, and one-twentieth of a revolution of the shaft 62, upon the tenth rotation of the cylinder 18, under the

95

control of the first tooth of said gear 69, a riser 64 upon the disk 60 will be brought to a position which will impart an upward movement to the controller bar 53 and thus move the cams 55 and 56 in the path of

100

movement of the member 40 of the mechanism B. Upon the second stage, which will be the operative engagement of the second tooth of the gear 69 with the Geneva stop gear 68, the said disk 60 will receive a second impulse amounting to one-twentieth of a revolution thereof and thus permit the bar 53 to descend to its former normal inoperative relation to the member 40 of the mechanism B.

105

The same condition is present with relation to the disk 61, it being understood that the tooth 66 of this disk will become operative with relation to the controller bar 54 only upon the one-hundredth rotation of the cylinder 18. Each stage results from an upward movement of the lift

110

bar 77.

115

To summarize, the operative effect of the actuating mechanism for the controller mechanism co-operating with the mechanisms A, B and C, is to maintain the controller mechanism for the mechanism A in the normally operative position at all times; to actuate the controller mechanism for the

120

mechanism B once during each ten rotations of the cylinder 18 by bringing it into the operative relation to said mechanism B; and upon the next rotation moving it out of said relation; and to actuate the controller mechanism for the mechanism C in the same man-

125

130

ner as the controller mechanism for the mechanism B excepting upon every hundredth rotation of the cylinder 18.

It is to be noted that the transfer operation as to the various numbering heads carried by the cylinder 18 is effected by the actuation of the controller bars 53 and 54 as described, as to the digits wheels of the lower three denominations, and not by transfer mechanisms in the numbering heads themselves, and that at all times, even while the digit wheels are being turned, they are locked by the mechanism user for actuating same, or in other words they are so held as to be incapable of movement independently of said actuating mechanism, and are never disconnected therefrom.

Since the arms 37, 38 and 39 occupy a fixed position in relation to the cylinder 18, it is apparent that the various numbering heads must be positioned upon said cylinder with relation to said arms so as to cause the actuation of the digit wheels only after the completion of the printing interval, and before the succeeding inking interval. The various arms 37, 38 and 39 extend along the same radius of the cylinder 18, which ensures simultaneous actuation of the gears 34, 35 and 36, when the progressive actuation of the machine requires it. This is not absolutely essential, but contributes toward simplicity in the design of the machine.

It is to be noted that no springs of any kind are required in the machine or in the numbering heads actuated thereby, and that all of the movements in the machine are positive movements excepting the restoration of the bars 53 and 54 and the actuating mechanism therefor to normal, gravity being relied upon to ensure the desired return movement of said parts after each actuation thereof. The weight of the parts will be sufficient to ensure this gravity return movement thereof, but in a machine of the dimensions as large as those of the machine of this application, the space is ample to permit the use of large strong springs if desired, without introducing into the machine those factors of uncertainty arising from the presence of many small springs in the numbering heads themselves.

If it be desired to stop the making of impressions by the machine, it is merely necessary to press the pedal 95. The result of pressing this pedal will be the simultaneous movement of the impression cylinder 15 out of the printing relation to the numbering heads 22 upon the cylinder 18; of the arm 99 by the link 98, sufficient to move the member 78 out of engaging relation to the cam 79; and downward movement of the frame 63 as a result of the oscillation of the lever 101 by the link 100, sufficient to move all of the bars 52, 53 and 54 out of the operative relation with the mechanisms A, B and C.

The slight lost motion of the dog 76 and the ratchet wheel 71, as indicated more particularly in Fig. 8, is for the purpose of permitting that relative movement of the frame 63 and the crank arm 74 upon the actuation 70 of the throwoff mechanism.

Since the throwoff mechanism is actuated by the pressmen only immediately following the completion of an impression, or immediately preceding the making of an impression, it is apparent that the various digit wheels will all be automatically set for the succeeding impression at the time of the actuation of this mechanism, and that thereafter, all of the parts in the machine will 80 remain in exactly the same relation until the throwoff mechanism is again actuated to place the machine in operation. During the time that the throwoff mechanism maintains the parts out of the operative relation, the 85 mechanisms operative upon the numbering heads are inoperative so that if desired, power may be applied to the machine without changing any of the digit wheels. Hence resetting of the numbering heads upon the 90 resumption of a run, is not required.

It is obvious that with a machine embodying the essential characteristics of my invention, no cutting of the inking rolls is required to avoid actuation of the numbering 95 heads thereby.

It is apparent that in a machine embodying my invention, there may be various changes in design, while still securing the same operative effect, it being possible to 100 dispense with some of the mechanisms in the machine such as the pawl 80 and the particular construction of pawls 83 and 84, which are used merely to ensure against any possible variation in the movements of other 105 mechanisms in the machine, the possibility of such variation being very remote without these particular mechanisms. Also the form of the cam 79 may be varied from that shown, in order to control the timing of the operative 110 interval of the disks 60 and 61.

Throughout the specification, I have used the term actuating mechanisms A, B and C to designate those mechanisms carried and rotatable with the numbering head cylinder, which in their function act directly upon the gears 34, 35 and 36. I have used the term controlling mechanism as designating the bars 52, 53 and 54, and their appurtenances, which act upon said mechanisms A, B and C for determining their operative interval, and have used the term actuating mechanism for the controlling mechanism to designate those parts of the machine actuated from the printing couple 125 for imparting the necessary movement to the bars 52, 53 and 54.

It is not my intention to limit the invention to the details of construction shown, it being apparent that various mechanisms in 130

the machine are capable of wide variation without departing from the spirit and scope of the invention.

Having described the invention, what I claim as new and desire to have protected by Letters Patent, is:—

1. A numbering machine embodying therein an impression cylinder, a numbering head cylinder, a member adapted to constantly engage the actuating member of a numbering head upon said numbering head cylinder, means whereby said member is rotated with said numbering head cylinder, about an axis coincident therewith, and means operative to impart unidirectional movement to said member independently of its movement with said numbering head cylinder during each rotation of the latter, whereby actuation of the numbering head is prevented at all times excepting when said last named means is operative.

2. A numbering machine embodying therein an impression cylinder, a numbering head cylinder, a plurality of members adapted respectively to constantly engage the actuating members of the units digit wheel, and wheels of higher denomination, of a numbering head upon said numbering head cylinder, means whereby said members are rotated with said numbering head cylinder about an axis coincident therewith, means severally operative upon said members to impart movement thereto independently of their movement with said numbering head cylinder during the rotation of the latter, whereby actuation of the digit wheels of the numbering head is prevented at all times excepting when said last named means are respectively operative upon said members, and means differentially operating to progressively actuate said last named means, to cause said members to impart timely actuation to the units digit wheel, and the wheels of higher denomination of said numbering head.

3. A numbering machine embodying therein an impression cylinder, a numbering head cylinder, a member adapted to constantly engage the actuating member of a numbering head upon said numbering head cylinder, means whereby said member is rotated with said numbering head cylinder, about an axis coincident therewith, means operative to impart unidirectional movement to said member independently of its movement with said numbering head cylinder during each rotation of the latter, whereby actuation of the numbering head is prevented at all times excepting when said last named means is operative, and a throwoff mechanism simultaneously operative to impart relative movement to said impression, and said numbering head cylinders to prevent the making of impressions thereby, and to make said last named means inoperative to impart movement to said member.

4. A numbering machine embodying therein an impression cylinder, a numbering head cylinder, a plurality of members adapted respectively to constantly engage the actuating members of the units digit wheel, and wheels of higher denomination, of a numbering head upon said numbering head cylinder, means whereby said members are rotated with said numbering head cylinder about an axis coincident therewith, means severally operative upon said members to impart movement thereto independently of their movement with said numbering head cylinder during the rotation of the latter, whereby actuation of the digit wheels of the numbering head is prevented at all times excepting when said last named means are respectively operative upon said members, means differentially operating to progressively actuate said last named means, to cause said members to impart timely actuation to the units digit wheel, and the wheels of higher denomination of said numbering head.

5. A numbering machine embodying therein an impression cylinder, a numbering head cylinder, a gear idly mounted to rotate about the same axis as said numbering head cylinder and adapted to constantly mesh with a gear operative upon a digit wheel of a numbering head carried thereby, an actuating mechanism for said gear whereby it is operatively connected to, and receives rotary movement from, said numbering head cylinder, and a controlling mechanism operative upon said actuating mechanism whereby said gear will receive movement, through said actuating mechanism, independently of its movement with said numbering head cylinder.

6. A numbering machine embodying therein an impression cylinder, a numbering head cylinder, a plurality of gears idly mounted to rotate about the same axis as said numbering head cylinder and adapted respectively to constantly mesh with a gear operative upon the units digit wheel and digit wheels of higher denomination, of a numbering head carried thereby, an actuating mechanism for each of said gears whereby it is operatively connected to, and receives rotary movement from, said numbering head cylinder, controlling members co-operating with said actuating mechanisms respectively, means whereby one of said controlling members is maintained in the operative relation to the actuating mechanism operative upon the gear operative upon the units digit wheel upon succeeding rotations of said numbering head.

- cylinder, means whereby said other controlling members are progressively brought into and out of their operative relation to their co-operating actuating mechanisms, an intermittent mechanism operative upon said last named means, and means whereby said intermittent mechanism will receive an impulse during each rotation of said numbering head cylinder.
10. A numbering machine embodying therein an impression cylinder, a numbering head cylinder, a gear idly mounted to rotate about the same axis as said numbering head cylinder and adapted to constantly mesh with a gear operative upon a digit wheel of a numbering head carried thereby, an actuating mechanism for said gear whereby it is operatively connected to, and receives rotary movement from, said numbering head cylinder, a controlling mechanism operative upon said actuating mechanism whereby said gear will receive movement, through said actuating mechanism, independently of its movement with said numbering head cylinder, and a throwoff mechanism operative simultaneously to impart relative movement to said impression and said numbering head cylinders, to prevent the making of impressions thereby, and to make said controlling mechanism inoperative with relation to said actuating mechanism.
8. A numbering machine embodying therein an impression cylinder, a numbering head cylinder, a plurality of gears idly mounted to rotate about the same axis as said numbering head cylinder and adapted respectively to constantly mesh with a gear operative upon the units digit wheel and digit wheels of higher denomination, of a numbering head carried thereby, an actuating mechanism for each of said gears whereby it is operatively connected to, and receives rotary movement from, said numbering head cylinder, controlling members co-operating with said actuating mechanisms respectively, means whereby one of said controlling members is maintained in the operative relation to the actuating mechanism operative upon the gear operative upon the units digit wheel upon succeeding rotations of said numbering head cylinder, means whereby said other controlling members are progressively brought into and out of their operative relation to their co-operating actuating mechanisms, an intermittent mechanism operative upon said last named means, means whereby said intermittent mechanism will receive an impulse during each rotation of said numbering head cylinder, and a throwoff mechanism operative simultaneously to impart relative movement to said impression and said numbering head cylinders, to prevent the making of impressions thereby, and to make said controlling members inoperative with relation to the actuating mechanisms with which they respectively co-operate.
9. A numbering machine embodying therein an impression cylinder, a numbering head cylinder, a gear idly mounted to rotate about the same axis as said numbering head cylinder and adapted to constantly mesh with a gear operative upon a digit wheel of a numbering head carried thereby, an arm carried by and rotatable with said numbering head cylinder, a locking member pivotally mounted thereon having a plurality of teeth adapted respectively and alternately to mesh with said first named gear, a toothed dog pivotally mounted adjacent some of said teeth upon said member, and a controlling mechanism operative upon said member and upon said dog whereby said first named gear will at all times be operatively connected to, and receive rotary movement from, said numbering head cylinder, and will, as a result of the oscillatory movement of said member, receive movement independently of its movement with said numbering head cylinder.
10. A numbering machine embodying therein an impression cylinder, a numbering head cylinder, a gear idly mounted to rotate about the same axis as said numbering head cylinder and adapted to constantly mesh with a gear operative upon a digit wheel of a numbering head carried thereby, an arm carried by and rotatable with said numbering head cylinder, a locking member pivotally mounted thereon having a plurality of teeth adapted respectively and alternately to mesh with said first named gear, a toothed dog pivotally mounted adjacent some of said teeth upon said member, a controlling bar having a cam thereon in the path of movement of said locking member, cams upon said member whereby alternate opposite oscillations will be imparted thereto when passing said first named cam, a second cam upon said bar arranged in the path of movement of said dog, whereby the engagement of said dog with said gear is assured, and means whereby said bar may be held with said cams in the operative relation to said member and said dog.
11. A numbering machine embodying therein an impression cylinder, a numbering head cylinder, a gear idly mounted to rotate about the same axis as said numbering head cylinder and adapted to constantly mesh with a gear operative upon a digit wheel of a numbering head carried thereby, an arm carried by and rotatable with said numbering head cylinder, a locking member pivotally mounted thereon having a plurality of teeth adapted respectively and alternately to mesh with said first named gear, a toothed dog pivotally mounted adjacent some of said teeth upon said member, a controlling mechanism operative upon

5 said member and upon said dog whereby said first named gear will at all times be operatively connected to, and receive rotary movement from, said numbering head cylinder, and will, as a result of the oscillatory movement of said member, receive movement independently of its movement with said numbering head cylinder, and a throwoff mechanism operative simultaneously to impart relative movement to said impression and said numbering head cylinders, to prevent the making of impressions thereby, and to make said controlling mechanism inoperative with relation to said locking member.

10 12. A numbering machine embodying therein an impression cylinder, a numbering head cylinder, a gear idly mounted to rotate about the same axis as said numbering head cylinder and adapted to constantly mesh with a gear operative upon a digit wheel of a numbering head carried thereby, an arm carried by and rotatable with said numbering head cylinder, a locking member pivotally mounted thereon having a plurality of teeth adapted respectively and alternately to mesh with said first named gear, a toothed dog pivotally mounted adjacent some of said teeth upon said member, a controlling bar having a cam thereon in the path of movement of said locking member, cams upon said member whereby alternate opposite oscillations will be imparted thereto when passing said first named cam, a second cam upon said bar arranged in the path of movement of said dog, whereby the engagement of said dog with said gear is assured, means whereby said bar may be held with said cams in the operative relation to said member and said dog, and a throwoff mechanism operative simultaneously to impart relative movement to said impression and said numbering head cylinders, to prevent the making of impressions thereby, and to impart movement to said last named means away from said bars to move the cams upon said bars out of the operative relation to said member and said dog respectively.

15 13. A numbering machine embodying therein an impression cylinder, a numbering head cylinder, a plurality of gears idly mounted to rotate about the same axis as said numbering head cylinder and adapted respectively to constantly mesh with a gear operative upon the units digit wheel and digit wheels of higher denomination, of a numbering head carried thereby, a plurality of arms carried by and rotatable with said numbering head cylinder, one adjacent each of said first named gears, a plurality of locking members pivotally mounted upon said arms respectively, each of said members having a plurality of teeth adapted to respectively and alternately mesh with one of

20 said teeth upon said members respectively, controlling members cooperating with said locking members respectively, means whereby one of said controlling members is maintained in the operative relation to the locking member co-operating with the gear operative upon the units digit wheel upon succeeding rotations of said numbering head cylinder, means whereby said other controlling members are progressively brought into and out of their operative relation to the locking members with which they co-operate, an intermittent mechanism operative upon said last named means, and means whereby said intermittent mechanism will receive an impulse during each rotation of said numbering head cylinder.

25 14. A numbering machine embodying therein an impression cylinder, a numbering head cylinder, a plurality of gears idly mounted to rotate about the same axis as said numbering head cylinder and adapted respectively to constantly mesh with a gear operative upon the units digit wheel and digit wheels of higher denomination, of a numbering head carried thereby, a plurality of arms carried by and rotatable with said numbering head cylinder, one adjacent each of said first named gears, a plurality of locking members pivotally mounted upon said arms respectively, each of said members having a plurality of teeth adapted to respectively and alternately mesh with one of said first named gears, a plurality of dogs pivotally mounted adjacent some of said teeth upon said members respectively, a plurality of controlling bars co-operating with said locking members respectively, each of said bars having a cam thereon in the path of movement of its co-operating locking member, cams upon each of said locking members whereby said member will receive alternate, opposite oscillations when passing the co-operating cam upon said bar, a second cam upon each of said bars arranged in the path of movement of the dog carried by the bar with which it co-operates, whereby the engagement of said dog with said gear is assured, means whereby one of said bars is maintained in the operative relation to the locking member co-operating with the gear operative upon the units digit wheel, means whereby said other bars are progressively brought into and out of their operative relation to the locking members with which they respectively co-operate, an intermittent mechanism operative upon said last named means, and means whereby said intermittent mechanism will receive an impulse during each rotation of said numbering head cylinder.

30 15. A numbering machine embodying therein an impression cylinder, a numbering head cylinder a plurality of gears idly

mounted to rotate about the same axis as said numbering head cylinder and adapted respectively to constantly mesh with a gear operative upon the units digit wheel and digit wheels of higher denomination, of a numbering head carried thereby, a plurality of arms carried by and rotatable with said numbering head cylinder, one adjacent each of said first named gears, a plurality of locking members pivotally mounted upon said arms respectively, each of said members having a plurality of teeth adapted to respectively and alternately mesh with one of said first named gears, a plurality of dogs pivotally mounted adjacent some of said teeth upon said members respectively, controlling members co-operating with said locking members respectively, means whereby one of said controlling members is maintained in the operative relation to the locking member co-operating with the gear operative upon the units digit wheel upon succeeding rotations of said numbering head cylinder, means whereby said other controlling members are progressively brought into and out of their operative relation to the locking members with which they co-operate, an intermittent mechanism operative upon said last named means, means whereby said intermittent mechanism will receive an impulse during each rotation of said numbering head cylinder, and a throwoff mechanism operative simultaneously to impart relative movement to said impression and said numbering head cylinders to prevent the making of impressions thereby and to impart movement to the respective means operative upon said controlling members, whereby said controlling members are brought out of the operative relation to said locking members and said dogs.

16. A numbering machine embodying therein an impression cylinder, a numbering head cylinder, a plurality of gears idly mounted to rotate about the same axis as said numbering head cylinder and adapted respectively to constantly mesh with a gear operative upon the units digit wheel and digit wheels of higher denomination, of a numbering head carried thereby, a plurality of arms carried by and rotatable with said numbering head cylinder, one adjacent each of said first named gears, a plurality of locking members pivotally mounted upon said arms respectively, each of said members having a plurality of teeth adapted to respectively and alternately mesh with one of said first named gears, a plurality of dogs pivotally mounted adjacent some of said teeth upon said members respectively, a plurality of controlling bars co-operating with said locking members respectively, each of said bars having a cam thereon in the path of movement of its co-operating locking member, cams upon each of said locking members

whereby said member will receive alternate, opposite oscillations when passing the co-operating cam upon said bar, a second cam upon each of said bars arranged in the path of movement of the dog carried by the bar with which it co-operates, whereby the engagement of said dog with said gear is assured, means whereby one of said bars is maintained in the operative relation to the locking member co-operating with the gear operative upon the units digit wheel, means whereby said other bars are progressively brought into and out of their operative relation to the locking members with which they respectively co-operate, an intermittent mechanism operative upon said last named means, means whereby said intermittent mechanism will receive an impulse during each rotation of said numbering head cylinder, and a throwoff mechanism operative simultaneously to impart relative movement to said impression and said numbering head cylinders to prevent the making of impressions thereby, and to impart movement to the several means co-operating with said bars to move the cams upon said bars out of the operative relation to said members and said dogs respectively.

17. A numbering machine embodying therein an impression cylinder, a numbering head cylinder, a plurality of gears idly mounted to rotate about the same axis as said numbering head cylinder and adapted respectively to constantly mesh with a gear operative upon the units digit wheel and digit wheels of higher denomination, of a numbering head carried thereby, an actuating mechanism for each of said gears whereby it is operatively connected to, and receives rotary movement from, said numbering head cylinder, controlling members co-operating with said actuating mechanisms respectively, means whereby one of said controlling members is maintained in the operative relation to the actuating mechanism operative upon the gear operative upon the units digit wheel upon succeeding rotations of said numbering head cylinder, a plurality of disks co-operating with said other controlling members respectively, said disks having risers thereon co-operating respectively with said controlling members to bring them into and out of operative relation to their co-operating actuating mechanism, the risers upon said disks respectively being in the ratio of one to ten, an intermittent mechanism operative upon said disks, and means whereby said intermittent mechanism will receive an impulse during each rotation of said numbering head cylinder.

18. A numbering machine embodying therein an impression cylinder, a numbering head cylinder, a plurality of gears idly mounted to rotate about the same axis as said numbering head cylinder and adapted

respectively to constantly mesh with a gear operative upon the units digit wheel and digit wheels of higher denomination, of a numbering head carried thereby, an actuating mechanism for each of said gears whereby it is operatively connected to, and receives rotary movement from, said numbering head cylinder, controlling members co-operating with said actuating mechanisms respectively, means whereby one of said controlling members is maintained in the operative relation to the actuating mechanism operative upon the gear operative upon the units digit wheel upon succeeding rotations of said numbering head cylinder, a plurality of disks co-operating with said other controlling members respectively, said disks having risers thereon co-operating respectively with said controlling members to bring them into and out of operative relation to their co-operating actuating mechanism, the risers upon said disks respectively being in the ratio of one to ten, a Geneva stop gear having twenty teeth thereon, operative upon said disks respectively, a two-toothed gear co-operating with said Geneva stop gear, and means whereby said last named gear will receive an impulse during each rotation of said numbering head cylinder.

19. A numbering machine embodying therein an impression cylinder, a numbering head cylinder, a plurality of gears idly mounted to rotate about the same axis as said numbering head cylinder and adapted respectively to constantly mesh with a gear operative upon the units digit wheel and digit wheels of higher denomination, of a numbering head carried thereby, an actuating mechanism for each of said gears whereby it is operatively connected to, and receives rotary movement from, said numbering head cylinder, controlling members co-operating with said actuating mechanisms respectively, means whereby one of said controlling members is maintained in the operative relation to the actuating mechanism operative upon the gear operative upon the units digit wheel upon succeeding rotations of said numbering head cylinder, a plurality of disks co-operating with said other controlling members respectively, said disks having risers thereon co-operating respectively with said controlling members to bring them into and out of operative relation to their co-operating actuating mechanism, the risers upon said disks respectively being in the ratio of one to ten, a Geneva stop gear having twenty teeth thereon, operative upon said disks respectively, a two-toothed gear co-operating with said Geneva stop gear, a lift bar, a cam rotating in synchronism with said numbering head cylinder, means carried by said lift bar in engaging relation with said cam, and a pawl and ratchet mechanism actuated by said lift bar and operative upon

said two-toothed gear, whereby said last named gear will receive an impulse during each rotation of said numbering head cylinder.

20. A numbering machine embodying 70
therein an impression cylinder, a numbering
head cylinder, a plurality of gears idly
mounted to rotate about the same axis as
said numbering head cylinder and adapted
respectively to constantly mesh with a gear
operative upon the units digit wheel and
digit wheels of higher denomination, of a
numbering head carried thereby, an actuating
mechanism for each of said gears whereby
it is operatively connected to, and re-
ceives rotary movement from, said number-
ing head cylinder, controlling members co-
operating with said actuating mechanisms
respectively, means whereby one of said con-
trolling members is maintained in the oper-
ative relation to the actuating mechanism
operative upon the gear operative upon the
units digit wheel upon succeeding rotations of
said numbering head cylinder, a shaft, a plu-
rality of disks carried thereby and co-operat-
ing with said other controlling members re-
spectively, said disks having risers thereon
co-operating respectively with said control-
ling members to bring them into and
out of operative relation to their co-oper-
ating actuating mechanism, the risers upon
said disks, respectively being in the ratio
of one to ten, a Geneva stop gear having
twenty teeth thereon, carried by said shaft
and operative upon said disks respectiv-
ely, a shaft counter to said first named
shaft, a two-toothed gear carried thereby
and co-operating with said Geneva stop gear,
a cam rotating in synchronism with said
numbering head cylinder, a lift bar, means
carried by said lift bar in engaging relation
with said cam, two ratchet wheels with their
teeth oppositely set, carried by said last
named shaft, a swing arm connected with
said lift bar, a pawl carried thereby co-oper-
ating with one of said ratchet wheels, two
pawl co-operating with said other ratchet
wheel, said pawls having cam slots therein,
and a pin carried by said swing arm and mov-
ing in said cam slots respectively, said slots
being so formed that movement of said
swing arm will impart movement to said
pawls in opposite directions, whereby when
one of them is disengaged from one ratchet
tooth, the other will be brought into engag-
ing relation with the adjacent ratchet tooth
of said ratchet wheel, and limit movement of
said shaft carrying said ratchet wheel to the
distance between succeeding teeth thereon.

21. A numbering machine embodying 125
therein an impression cylinder, a numbering
head cylinder, a plurality of gears idly
mounted to rotate about the same axis as said
numbering head cylinder and adapted re- 130
spectively to constantly mesh with a gear

operative upon the units digit wheel and digit wheels of higher denomination, of a numbering head carried thereby, an actuating mechanism for each of said gears where-
5 by it is operatively connected to, and receives rotary movement from, said numbering head cylinder, controlling members co-operating with said actuating mechanisms respectively, means whereby one of said controlling mem-
10 bers is maintained in the operative relation to the actuating mechanism operative upon the gear operative upon the units digit wheel upon succeeding rotations of said numbering head cylinder, a plurality of disks co-operat-
15 ing with said other controlling members re-
spectively, said disks having risers thereon co-operating respectively with said control-
ling members to bring them into and out of operative relation to their co-operating actu-
20 ating mechanism, the risers upon said disks respectively being in the ratio of one to ten, an intermittent mechanism operative upon said disks, means whereby said intermittent mechanism will receive an impulse during each ro-
25 tation of said numbering head cylinder, and a throwoff mechanism operative si-
multaneously to impart relative movement to said impression and said numbering head cylinders, to prevent the making of impres-
30 sions thereby, and to make said controlling mechanism inoperative with relation to said actuating mechanism.

22. A numbering machine embodying therein an impression cylinder, a numbering head cylinder, a plurality of gears idly mounted to rotate about the same axis as said numbering head cylinder and adapted re-
35 spectively to constantly mesh with a gear op-
erative upon the units digit wheel and digit
40 wheels of higher denomination, of a numbering head carried thereby, a plurality of arms carried by and rotatable with said numbering head cylinder, one adjacent each of said first named gears, a plurality of locking
45 members pivotally mounted upon said arms respectively, each of said members having a plurality of teeth adapted to respectively and alternately mesh with one of said first named gears, a plurality of dogs pivotally
50 mounted adjacent some of said teeth upon said members respectively, a plurality of controlling bars co-operating with said locking
55 members respectively, each of said bars having a cam thereon in the path of movement of its co-operating locking member, cams upon each of said locking members whereby said member will receive alternate, opposite oscillations when passing the co-operating cam upon said bar, a second cam
60 upon each of said bars arranged in the path of movement of the dog carried by the bar with which it co-operates, whereby the engagement of said dog with said gear is as-
65 sured, means whereby one of said bars is maintained in the operative relation to the

locking member co-operating with the gear operative upon the units digit wheel, a plurality of disks co-operating with said other controlling members respectively, said disks having risers thereon co-operating respec-
70 tively with said controlling members to bring them into and out of operative relation to their co-operating actuating mechanism, the risers upon said disks respectively being in the ratio of one to ten, an intermit-
75 tent mechanism operative upon said disks, and means whereby said intermittent mechanism will receive an impulse during each ro-
80 tation of said numbering head cylinder.

23. A numbering machine embodying therein an impression cylinder, a numbering head cylinder, a plurality of gears idly mounted to rotate about the same axis as said numbering head cylinder and adapted respectively to constantly mesh with a gear op-
85 erative upon the units digit wheel and digit wheels of higher denomination, of a numbering head carried thereby, a plurality of arms carried by and rotatable with said numbering head cylinder, one adjacent each of said first named gears, a plurality of locking
90 members pivotally mounted upon said arms respectively, each of said members having a plurality of teeth adapted to respectively and alternately mesh with one of said first named gears, a plurality of dogs pivotally mounted adjacent some of said teeth upon said members respectively, a plurality of controlling bars co-operating with said locking members respectively, each of said bars having a cam thereon in the path of movement of its co-operating locking member, cams upon each of said locking members whereby said member will receive alternate, opposite oscillations when passing the co-operating cam upon said bar, a second cam upon each of said bars arranged in the path of movement of the dog carried by the bar with which it co-operates, whereby the engagement of said dog with said gear is assured, means whereby one of said bars is maintained in the operative relation to the locking member co-operating with the gear operative upon the units digit wheel, a plurality of disks co-operating with said other controlling members respectively, said disks having risers thereon co-operating respec-
95 tively with said controlling members to bring them into and out of operative relation to their co-operating actuating mechanism, the risers upon said disks respectively being in the ratio of one to ten, an intermit-
100 tent mechanism operative upon said disks, and means whereby said intermittent mechanism will receive an impulse during each ro-
105 tation of said numbering head cylinder, and a throwoff mechanism operative simultaneously to impart relative movement to said impression and said numbering head cylinders to prevent the making of impressions thereby

and to move said disks out of the operative relation to said bars, whereby said bars are brought out of the operative relation to said locking members and said dogs.

5 24. A numbering machine embodying therein an impression cylinder, a numbering head cylinder, a plurality of gears idly mounted to rotate about the same axis as said numbering head cylinder and adapted 10 respectively to constantly mesh with a gear operative upon the units digit wheel and digit wheels of higher denomination, of a numbering head carried thereby, an actuating mechanism for each of said gears 15 whereby it is operatively connected to, and receives rotary movement from, said numbering head cylinder, controlling members co-operating with said actuating mechanisms respectively, means whereby one of said controlling members is maintained in the operative relation to the actuating mechanism operative upon the gear operative upon the units digit wheel upon succeeding rotations of said numbering head cylinder, means 20 whereby said other controlling members are progressively brought into and out of their operative relation to their co-operating actuating mechanisms, an intermittent mechanism operative upon said last named means, 25 means whereby said intermittent mechanism will receive an impulse during each rotation of said numbering head cylinder, and a throwoff mechanism operative simultaneously to impart relative movement to said impression and said numbering head cylinders 30 to prevent the making of impressions thereby, to make said controlling mechanism inoperative with relation to said actuating mechanism, and to make said last named means inoperative with relation to said intermittent mechanism.

40 25. A numbering machine embodying therein an impression cylinder, a numbering head cylinder, a gear idly mounted to rotate about the same axis as said numbering head cylinder and adapted to constantly mesh with a gear operative upon a digit wheel of a numbering head carried thereby, an arm carried by and rotatable with said numbering head cylinder, a locking member pivotally mounted thereon having a plurality of teeth adapted respectively and alternately to mesh with said first named gear, a toothed dog pivotally mounted adjacent some of said teeth upon said member, means carried by said dog and operatively engaging said gear whereby relative movement of said dog with relation to said gear is limited, and a controlling mechanism operative 50 upon said member and upon said dog whereby said first named gear will at all times be operatively connected to, and receive rotary movement from, said numbering head cylinder, and will, as a result of the oscillatory movement of said member, receive

movement independently of its movement with said numbering head cylinder.

26. A numbering machine embodying therein an impression cylinder, a numbering head cylinder, a plurality of gears idly mounted to rotate about the same axis as said numbering head cylinder and adapted respectively to constantly mesh with a gear operative upon the units digit wheel and digit wheels of higher denomination, of a numbering head carried thereby, a plurality of arms carried by and rotatable with said numbering head cylinder, one adjacent each of said first named gears, a plurality of locking members pivotally mounted upon said arms respectively, each of said members having a plurality of teeth adapted to respectively and alternately mesh with one of said first named gears, a plurality of dogs pivotally mounted adjacent some of said teeth upon said members respectively, each of said dogs being provided with means co-operating with the gear with which said dog co-acts to limit the movement of said dog relative to said gear, controlling members co-operating with said locking members respectively, means whereby one of said controlling members is maintained in the operative relation to the locking member co-operating with the gear operative upon the units digit wheel upon succeeding rotations of said numbering head cylinder, means whereby said other controlling members are progressively brought into and out of their operative relation to the locking members with which they co-operate, an intermittent mechanism operative upon said last named means, and means whereby said intermittent mechanism will receive an impulse during each rotation of said numbering head cylinder.

45 27. A numbering machine embodying therein an impression cylinder, a numbering head cylinder, a circumferentially extending flange thereon, slotted circular end plates therefor whereby the frame of a numbering head mechanism is rigidly supported intermediate said end plates by said flange, and may receive adjustment circumferentially of said cylinder, a gear idly mounted to rotate about the same axis as said numbering head cylinder and adapted to constantly mesh with a gear operative upon a digit wheel of a numbering head carried thereby, an actuating mechanism for said gear whereby it is operatively connected to, and receives rotary movement from, said numbering head cylinder, and a controlling mechanism operative upon said actuating mechanism whereby said gear will receive movement, through said actuating mechanism, independently of its movement with said numbering head cylinder.

In witness whereof I have hereunto affixed my signature this 23d day of April, 1924.

JAMES H. REINHARDT.
